METHOD AND APPARATUS FOR FORMING A SEAM IN A BARREL OR THE LIKE

James J. McGarry, Buffalo, N. Y., assignor to Niagara Machine & Tool Works, Buffalo, N. Y., a corporation of New York

Application March 24, 1934, Serial No. 717,249

6 Claims. (Cl. 113—54)

This invention relates to a method and apparatus for forming a Gordon or box seam between the two ends of a piece of sheet metal so as to unite the ends in the form of a tubular shell preparatory to the operations of forming the ends of the barrel to receive heads. The Gordon seam is illustrated in the Gordon Patent No. 631,487. Barrels having Gordon seams are largely used for one trip containers or for containers for materials other than liquids. The Gordon seam, in general, comprises T-shaped interlocking ribs provided inwardly from the edges of the sheets to be seamed together, the surplus material beyond the seam being left uncut. As heretofore made this seam was formed by pressing channels into the edges to be connected, interfitting the channels, tucking the side walls of the channels by means of tucking rolls so as to bring them into contact with one another and then rolling down the crown of the seam. This necessitated a forming machine with rollers at right angles to one another, since the tucking rolls first operating were required to have their axes projecting outwardly from the face of the sheet while the finishing roll was required to have its axis parallel or tangential to the face of the seam. This required a complicated drive and moreover required the provision of elaborate adjusting means, since careful adjustment of the tucking rolls was required both to properly bring in the sides of the channel and also to insure the proper registry of the secondary roller.

It is one of the principal objects of this invention to provide a method of forming a Gordon or box seam which permits it to be rolled by pairs of rollers all of which have their axes parallel with one another and which are thereby driven by a simple gear train and also require adjustment in one direction only and in which the rollers of each pair are arranged on opposite sides of the plane of the sheets being seamed together. A further object of this invention is to provide such a seam which can be formed on either side of a barrel or the like, that is, on the inside or the outside.

Another purpose of the invention is to provide a seam which can be rolled without distortion of the work being operated on, that is, in which there is no tendency for the material to curve or belly in going through the machine.

Another purpose is to provide a method of rolling the Gordon seam which insures a tighter seam than with methods heretofore carried out. Specifically, the present method holds and stretches the metal at the bends of the seam so as

to secure tight interlocking whereas the tendency of the standard method of rolling this seam is to push the metal apart and spread the seam. By providing a tighter seam in accordance with the present invention, the seam is not only less likely to leak but the same is stronger and the containers less liable to be injured in transit.

Another object of the present invention is to provide a method which can be practiced with rolls of ordinary form and in which the machine is of sturdy construction and will operate for a long period of time without getting out of order or requiring repairs or attention.

In the accompanying drawings:

Fig. 1 is a side elevation of a compound seam closing machine suitable for carrying out my invention.

Fig. 2 is a fragmentary end view thereof, taken on line 2—2, Fig. 1.

Fig. 3 is a vertical longitudinal section, taken on line 3—3, Fig. 2.

Fig. 4 is a fragmentary view of the two edges of a barrel shell showing the manner in which channels are provided preparatory to the seaming operation in the seam closer showing in Figs. 1—3.

Figs. 5, 6 and 7 are fragmentary vertical transverse sections taken on the correspondingly numbered lines on Fig. 3 and showing the successive stages in closing the seam in accordance with my invention.

Fig. 8 is a view similar to Fig. 4 showing the manner in which two channels are provided preparatory to the seaming operation with the modified form of rolls shown in Figs. 9, 10 and 11.

Figs. 9, 10 and 11 are views similar to Figs. 5, 6 and 7 and showing modified forms of rolls which can be used for rolling the channeled form shown in Fig. 8 into a Gordon seam.

The seam made in accordance with the disclosure of Figs. 1—7 is illustrated in connection with a barrel shell 10 having two edges 11 and 12 which are adapted to be united by the seam in accordance with my invention. It will be understood, however, that the invention is not necessarily limited to forming barrel seams but can be practiced wherever a Gordon seam is desired. The preparation usually accomplished in a press with dies (not shown) consists in the formation of two channels 13 and 14 along the adjacent edges 11 and 12 of the barrel shell. One fits into the other, as indicated in Fig. 4. In carrying out the invention, as shown in Figs. 1—7, instead of providing simple channels as has been the practice heretofore, however, each of the channels 13 and 14 is specially formed so that its

crown 15 is arranged on one side of the sheet being seamed, while the base 16 of the channel is arranged on the opposite side of the sheet being formed and the base or legs of the channel are connected to the sheet by diagonal webs 17. It will therefore be apparent that the preliminary forming of the shell provides a central channel which opens toward one side of the sheet and two V-shaped channels on either side of the central channel which open toward the opposite side of the shell. In forming the Gordon seam any material in excess of that required to form the seam simply projects beyond the seam, as indicated at 18. By leaving the excess material it is unnecessary to cut and trim the sheets to exact length and squareness as would be necessary with an ordinary lock seam. It will be understood that the excess material is rarely sufficient to project out from the seaming when it is finally rolled and that the projection shown in the drawings at 18 represents an exaggerated condition.

Channels formed as indicated in Fig. 4, are interfitted and laid over the horn 20 of the compound seam closing machine 21 illustrated in the other figures. This machine comprises a base 22 and a pedestal 23 rising from this base and from which the horn 20 projects outwardly in one direction. The pedestal is also formed to provide a head 24 which projects outwardly over the horn 20 so as to form a jaw between the head and the horn. In the outer end of the horn are mounted three non-power driven lower seam closing rolls 25, 26 and 27 and these rolls cooperate with companion power driven upper forming rolls 28, 29 and 30. Each of these rolls is mounted with its axis horizontally disposed and extending at right angles to the major axis of the machine frame and the barrel shell travels successively between the companion rolls. The three lower rolls 25, 26 and 27 are mounted in a frame 31 which is removably mounted in the outer end of the horn 20. Each of these rolls is also individually adjustable as to height by means of adjusting screws 32 which can be connected to the bearing blocks for the rolls in any usual and well known manner.

The power driven forming rolls 28, 29 and 30 are suitably journalled in the outer end of the head 24 and fixed to the shaft of each of these power driven rolls is a pinion 33. These pinions 33 are driven by intermediate gears 34 and 35 from a gear 36 fixed to a cross shaft 37. A large drive gear 38 is also fixed to the shaft 37 and this is driven by a pinion 39 on a main drive shaft 40. This drive shaft is driven by a pulley and belt connection 41 with an electric motor 42, this motor being also preferably mounted on the head 24. It will be seen that from this gearing the upper power rollers 28, 29 and 30 are all driven in the same direction and at the same speed. The barrel shell with its edges formed as shown in Fig. 4, are brought together over the horn 20 of the seamer, as indicated by dotted lines in Fig. 1, and the channels are interlocked. The interlocked channels are then lined up with the rolls and the shell is pushed into the rolls by a pusher which comprises a push rod 44 having a head 45 adapted to engage the end of the barrel shell, a bell crank lever 46 for operating the push rod, a shipper rod 47 for operating the bell crank lever and a shaft 48 having a treadle at one end and a rock lever at its opposite end, the rock lever being connected to the lower end of the shipper rod 47.

The first set of companion rolls 25 and 28 are best illustrated in Fig. 5. The upper power roll of this pair is of cylindrical form and has a central peripheral channel 49 which is of square form in cross section and the bottom of the channel is preferably milled or knurled, so as to provide a traction face which draws the barrel shell through the seamer and discharges it. This milled or knurled face engages the crown 15 of the channel 13. The companion roller 25 of this power roll 28 is of cylindrical form having a central V-shaped peripheral groove 50. The edges of the channel 50 are also preferably beveled, as indicated at 51, so that the diagonally extending sides 17 of the pre-formed channels are led into the V-shaped groove 50 which draws these sides together, as shown in Fig. 5. In this preliminary rolling step the two channels are interlocked and the sides 17 of the channels are brought tight against the sides of the main central channel. It is therefore apparent that this preliminary rolling provides two flanges 52 which are formed by closing the side channels in the pre-formed edges shown in Fig. 4.

In this form the partly closed seam passes on to the second set of companion rolls 26 and 29. The upper power driven roll of this pair is of substantially the same form as the roll 28 having a central peripheral knurled or milled channel 53 which bears against the crown of the bead 30 and forms a driver. The lower companion roll 26 is provided with a central peripheral V-shaped groove 54, as with the first roll 25 but this V-shaped channel is much shallower and the corners thereof are not beveled so that this roll 35 serves to press the flanges 52 upwardly and their edges into contact or abutment with one another.

The shell then passes on to the last pair of forming rolls 27 and 30. The power driven roll 30 has a central peripheral knurled channel 55 40 as with the other power driven rolls and its companion lower roll is perfectly cylindrical. These two rolls complete the Gordon seam by pressing the abutting flanges 52 upwardly from the position shown in Fig. 6 to the flat finished seam 45 shown in Fig. 7. In this last operation the material forming the seam is stretched so that a tight and strong interlocking seam is secured. This is effected by butting the flanges 52 together in the second operation so that the final 50 operation is not merely one of bending these flanges up into position but is also one of forcing the flanges together and pulling, compressing and stretching the metal into a tight fit.

It will be understood that, especially with 55 lighter gages of metal it is possible to perform the operation in accordance with my invention with two sets of rolls, eliminating the central pair 26 and 29. However, three pairs of rolls are preferred to secure a tight and strong seam and 60 also to hold the sheet metal shell against being curved or bellied in going through the seamer, the three alining pairs of rolls holding the seam in a straight line.

A modified manner in which the invention can 65 be carried out is shown in Figs. 8-11.

In carrying out the invention, as shown in these figures, the two edges 11a and 12a of the unseamed barrel shell 10a are formed with U-shaped channels both of which project laterally 70 in the same direction from the barrel shell. As shown in Fig. 8, these channels 13a and 14a project outwardly and have a flat crown and straight sides. As in the other form of the invention these channels are preferably preformed 75

In a press with suitable dies and the excess material 18a is left uncut so that it is unnecessary to trim the barrel shell to an exact length before seaming it.

5 The channels of the shell are interfitted and pass through three series of rolls, as in the preferred construction shown in Figs. 1-7, but the rolls are of somewhat different form necessitated by the different form of the channels preformed in the shell. As best shown in Fig. 9 the power roll 28a, which corresponds to the initial power roll 28 shown in Fig. 5, is of cylindrical form and has a relatively deep peripheral channel 49a, the bottom of which is milled or knurled. Its companion lower roll 25a is also of cylindrical form but is provided with a relatively deep V-shaped peripheral groove 50a which is substantially the same width as the groove 49a in the upper power driven roll 28a. In passing between the companion rolls 28a and 25a the channels 14a and 15a are deformed from the condition shown in Fig. 8 to the condition shown in Fig. 9. Thus, the channel is pressed downwardly with the result that its side walls are forced inwardly toward one another and also downwardly so as to form flanges 52a. After being drawn between the initial pair of forming rolls 28a and 25a the seam of the shell passes on between a second pair of rolls 28a and 26a which correspond to the rolls 29 and 26 of the form of the invention shown in Figs. 1-7 and are driven in the same manner. The power driven roll 29a is of substantially the same form as the initial power driven roll 28a but its milled central peripheral channel 53a is shallower. Similarly, its companion roll 26a is of substantially similar form to the initial lower roll 25a except that its central peripheral V-shaped channel 54a is shallower. When the seam passes between this second companion pair of rolls 28a and 26a the flanges 52a are forced upwardly into almost abutting relation and the crown of the channels is forced downwardly so that the seam takes the form shown in Fig. 10.

The seam so formed then passes between the last pair of companion rolls 30a and 27a which correspond to the rolls 30 and 27 of the form of the invention shown in Figs. 1-7 and are operated in like manner. The power driven roll 30a is substantially the same as the other two power driven rolls 28a and 29a except that its central knurled peripheral channel 55a is the shallowest. The lower roll 27a of this pair, instead of being cylindrical as with the roll 27, is provided with a very shallow central peripheral channel 60 having beveled sides 61. In passing through the very shallow channels 55a and 60 the Gordon seam is completed, the flanges 52a being pressed tightly together so as to force the corners of the crown into tight engagement and the crown of the bead being rolled down flat.

It is apparent with both forms of the invention shown that the Gordon seam is provided by a series of pairs of rolls, all of which have their axes parallel to one another and at right angles to the line of movement of the barrel being seamed. In this manner the drive for the rolls is extremely simple and as compared with prior compound seam closers for Gordon seams eliminates entirely the complicated drive necessitated by the use of special rolls to bring in the sides of the channel and which have their axes disposed at right angles to the other rolls. Moreover, the present invention eliminates the necessity for complicated adjustments and requires only that the lower rolls be vertically adjustable.

It is also apparent that with both forms of the invention shown, the seam can be formed on either side of the shell, that is, on the inside or the outside as may be desired. It is also apparent that with both methods disclosed the seam formed is tight and strong and will adequately stand up under the use to which barrels having Gordon seams are subjected.

It will be understood that the means for carrying out my invention can be varied and that therefore the invention is not to be construed as being limited to any particular form or mechanism disclosed except as limited by the appended claims in which by the term "box seam" is meant the Gordon or box seam disclosed and which is formed by providing the two sheets with channels or corrugations along zones spaced inwardly from the edges of the sheets and then pressing the overlapped corrugations into C form so that the seam is composed of six thicknesses of metal.

I claim as my invention:

1. The method of forming a box seam composed of six thicknesses of metal which comprises displacing a narrow zone of a metal blank in one direction to form a corrugation spaced inwardly from one edge thereof and composed of a crown and side walls, similarly forming another metal blank, placing the corrugation of one blank within the corrugation of the other blank, applying pressure to the top of the outer crown and to the opposite face of the inner blank to displace the interfitting corrugations bodily in the direction opposite from which they project and to displace the side portions of said interfitting corrugations toward one another and in converging relation, thereby to provide a partially formed seam, and further applying pressure to the top of the outer crown and to the opposite face of the inner blank to flatten said partially formed seam.

2. The method of forming a box seam composed of six thicknesses of metal which comprises displacing a narrow zone of a metal blank in one direction to form a corrugation spaced inwardly from one edge thereof and composed of a crown and side walls, similarly forming another metal blank, placing the corrugation of one blank within the corrugation of the other blank, passing said blanks between a pair of rolls, one applying pressure to the top of the outer crown and the other to the opposite face of the inner blank, said rolls displacing the interfitting corrugations bodily in the direction opposite from which they project and displacing the side portions of said interfitting corrugations toward one another and in converging relation thereby to provide a partially formed seam and thereafter passing said blanks between a second pair of rolls one of said last rolls applying pressure to the top of the outer crown and the other to the opposite face of said inner blank, said last named pair of rolls flattening said partially formed seam.

3. The method of forming a box seam composed of six thicknesses of metal which comprises displacing a narrow zone of a metal blank in one direction to form a corrugation spaced inwardly from one edge thereof and composed of a crown and side walls, similarly forming another metal blank, placing the corrugation of one blank within the corrugation of the other blank, passing said blanks between a pair of rolls each roll having a peripheral groove in line with said corrugations one applying pressure to the top of the outer crown and the other to the opposite face of the inner blank, said rolls displacing the interfitting corrugations bodily in the direction op-

posite from which they project and into the groove of said last named roll and displacing the side portions of said interfitted corrugations toward one another and in converging relation 5 thereby to provide a partially formed seam and thereafter passing said blanks between a second pair of rolls one of said last rolls applying pressure to the top of the outer crown and the other to the opposite face of said inner blank, said last 10 named pair of rolls flattening said partially formed seam.

4. The method of forming a box seam composed of six thicknesses of metal which comprises displacing a narrow zone of a metal blank in one direction to form a corrugation spaced inwardly from one edge thereof and composed of 15 a crown and side walls, similarly forming another metal blank, placing the corrugation of one blank within the corrugation of the other blank, passing said blanks between a pair of forming members one applying pressure to the top of the outer crown and the other to the opposite face of the inner blank, said forming members displacing the interfitted corrugations bodily 20 in the direction opposite from which they project and displacing the side portions of said interfitted corrugations toward one another and in converging relation thereby to provide a partially 25 formed seam and further applying pressure to the top of the outer crown and to the opposite face of the inner blank to flatten said partially formed seam.

5. A compound seaming machine for rolling a box seam composed of six thicknesses of metal 30 from preformed blanks each having a narrow zone displaced inwardly from one edge thereof to form a corrugation composed of a crown and side walls and the corrugation of one blank being placed within the corrugation of the other blank, comprising a frame, a series of pairs of 35 forming members mounted in said frame, means for propelling the interfitted blanks between said 40

pairs of forming members in succession, one forming member of the first pair being formed to apply pressure to the top of the outer crown and the other being formed to apply pressure to the opposite face of the inner blank, said first pair of forming members displacing the interfitted corrugations bodily in the direction opposite from which they project and displacing the side portions of said interfitted corrugations toward one another and in converging relation 10 thereby to provide a partially formed seam, and a subsequent pair of said forming members being formed to further apply pressure to the top of the outer crown and to the opposite face of the inner blank and flatten said partially formed 15 seam.

6. A compound seaming machine for rolling a box seam composed of six thicknesses of metal from preformed blanks each having a narrow zone displaced inwardly from one edge thereof 20 to form a corrugation composed of a crown and side walls and the corrugation of one blank being placed within the corrugation of the other blank, comprising a frame, a series of pairs of rolls mounted in said frame with their axes 25 parallel to one another, means for propelling the interfitted blanks between said pairs of rolls in succession, one roll of the first pair being formed to apply pressure to the top of the outer crown and the other being formed to apply pressure to the opposite face of the inner blank, said first pair of rolls displacing the interfitted corrugations bodily in the direction opposite from which they project and displacing the side portions 30 of said interfitted corrugations toward one another and in converging relation thereby to provide a partially formed seam, and a subsequent pair of said rolls being formed to further apply pressure to the top of the outer crown and to the opposite face of the inner blank and flatten 35 40 said partially formed seam.

JAMES J. McGARRY.
